UNITED STATES PATENT OFFICE

NEWTON H. HORNE, OF KANSAS CITY, MISSOURI

HYDRAULIC PULSATORE

Application filed November 3, 1928. Serial No. 316,962.

This invention relates to surgical appliances and more particularly to a pulsator adapted to be used to cure piles and internal ailments to which women are subject.

One object of the invention is to provide a device of this character which may be inserted into the rectum or vaginal passage and may serve as an applicator through the medium of which ointment may be applied to internal membranes while, at the same time, the head of the device which is inserted, may be caused to pulsate and thereby massage the muscles in order to strengthen the muscles and cause internal organs to be returned to their normal position.

Another object of the invention is to so form the device that water may be caused to flow through the head of the device while it is pulsating and thereby allow the head to be retained at either a high or low temperature, according to whether hot or cold water is used. By this arrangement the device may serve either as a hot or cold pack, according to the requirements of the ailment which is being treated.

Another object of the invention is to provide a device of this character in which a hot water bottle of a conventional construction may be employed as a main receptacle and thereby make it unnecessary to provide a special receptacle and, in addition, allow the receptacle to be used as a hot water bottle for other purposes.

The invention is illustrated in the accompanying drawings, wherein:

Figure 1 is a perspective view of the improved pulsator with fragments of its pipe shown in section.

Figure 2 is an enlarged view of the pulsator shown principally in longitudinal section.

Figure 3 is an enlarged fragmentary sectional view taken longitudinally through a coupling and associated parts of the device, the view being taken along the line 3-3 of Figure 2.

The improved pulsator constituting the subject matter of this invention includes a main receptacle 1 which consists of a hot water bottle of a conventional construction and is formed with the usual internally thread-

ed neck 2 to receive a threaded stopper when used as a water bottle. The pipe 3 of the device may be of any length desired and consists of sections 4 and 5 between which is disposed a bulb 6. At one end, the pipe 4 is engaged about the neck 7 of a hollow plug 8 of the proper size to be screwed into the neck 2 of the water bottle and this head 8 is formed with an outstanding annular flange 9 against which is disposed a gasket or washer 10 so that when the threaded end portion 11 is screwed into the neck 2 of the water bottle, a tight joint will be formed. It will thus be seen that when the head or coupling 8 is screwed into the neck of the water bottle and the water bottle placed upon a bed, table or other support, the water may flow through the coupling into the pipe.

The bulb 6 has its end portions internally thickened as shown at 12, to form attaching ends or necks and these end portions of the bulb are connected with the adjacent ends of the pipe sections 4 and 5 by couplings 13. These couplings are of a duplicate construction and each includes a thickened central portion 14 from which extend necks 15 terminating in enlarged heads 16 which taper outwardly toward their ends, as shown in Figure 3. The thickened end portions 12 of the bulb engage about the couplings between the enlarged intermediate portions 14 and the heads 16 at their inner ends and the adjacent ends of the pipe sections 4 and 5 engage about the outer necks of the couplings and the heads thereof.

Therefore, the bulb and the pipe sections will be firmly connected and, due to the tight binding engagement of the bulb and pipe sections with the couplings, there will be no danger of leakage. Check valves 16' are provided in the couplings, one opening inwardly and the other outwardly so that when the bulb is compressed water will be forced out of it into the pipe 5 and as the bulb expands a fresh supply of water is drawn through the pipe 4 from the water bottle.

The applicator or head 17 of the device is formed of soft rubber and has its outer surface roughened by diagonally extending ribs 18 crossing each other, as shown in Fig-

ure 1, and serving as scrapers as well as defining pockets 19. These pockets 19 will serve to receive ointment to be applied to internal membranes of a person being treated. This head or applicator is elongated and is closed except at its inner end, where an opening 20 is formed to receive a tube 21 formed of hard rubber, metal or any other desired rigid material. The tube 21, which is open at both ends, is formed with side openings 22 spaced from each other suitable distances longitudinally of the tube and the outer end portion of the tube is externally threaded, as shown at 23, so that the protruding end portion of the tube may be screwed into an internally threaded coupling or nipple 24 fitted into the end of the pipe section 5. A locking disc or washer 25 is threaded upon the tube 21 and disposed within the head, and from an inspection of Figure 2, it will be seen that when the tube is screwed into the coupling or nipple 24 the perforated end of the head will be firmly gripped between the nipple and the washer 25, thereby providing a tight joint and preventing leakage.

In order to permit water which has passed from the receptacle 1 through the pipe 3 into the head 17, to return to the receptacle, there has been provided a return tube indicated in general by the numeral 26 in Figure 1 of the drawings. This return tube is a great deal smaller than the pipe 3 and is formed of sections 27, 28 and 29 which extend respectively through the pipe section 4, bulb 6, and pipe section 5. Stems 30 formed of rigid material extend through the coupling 13 and these stems are surrounded by anchors 31 disposed near the ends of the stems. Each anchor consists of a strand of resilient wire bent to form a coil which fits tightly about the stem and the end portions of the wire strands form arms which project radially from the coil. Referring to Figure 3, it will be seen that the arms of the anchor at one end of the stem are fitted into openings formed in the head 16 of the coupling whereas the arms of the anchor at the other end of the stem bear against the outer end of the head of the coupling. By this arrangement the stems will be retained in proper position with respect to the couplings and they will not interfere with free flow of water through the couplings. In addition the anchors disposed within the couplings serve to limit outward movement of the check valves 16' away from their seats. The ends of the tube section 28 are engaged with the ends of the stems which protrude from the inner ends of the couplings 13 and the outer ends of the stems are engaged by the adjacent ends of the tube sections 27 and 29. It will thus be seen that the tube sections 27, 28 and 29 will be united and form a continuous passage for water returning to the receptacle. The tube section 27 is of such length that it passes

through the head or coupling 8 and into the receptacle 1, whereas the tube section 29 is of slightly less length than the pipe section 5 and, at its outer end, is engaged with a hollow stem 32 which is freely received in the tube 21 of the head 17.

When the device is in use the water bottle or receptacle 1 may be filled with hot or cold water according to the nature of the ailment to be treated and, if a cold application is desired, the water bottle may be packed in ice so that the water will be kept cold. After the head 17 has been inserted the bulb 6 is successively squeezed and released and as it is compressed and expands, pulsations will be imparted to the water with which the head 17 and the bulb and water pipe have become filled. These pulsations will cause the head 17, which is formed of soft rubber, to expand and contract and the internal muscles about the head will be massaged. As the head contracts, the water is forced through the small tube back into the water bottle. Therefore, a circulation is established. Ointment or other medicine applied to the head and received in the pockets 19 will be applied to the membranes and, therefore, the device may be used both as an applicator for applying ointment to internal muscles and as means for massaging the muscles and causing the muscles and organs controlled thereby to assume their natural positions.

What is claimed is:

1. In a massaging device, a fluid receptacle, a pipe leading therefrom, a hollow head of elastic material at the other end of said pipe having communication with the receptacle through the pipe whereby fluid in the receptacle may flow through the pipe into the head, a bulb intermediate the length of said pipe which when compressed and allowed to expand will cause fluid in the pipe and head to pulsate with resulting expansion and contraction of the head, and a return tube for the fluid extending through the pipe and bulb with one end communicating with the head and its other end communicating with the receptacle.

2. In a massaging device, a fluid receptacle, a pipe leading therefrom, a hollow head of elastic material at the other end of said pipe having communication with the pipe whereby fluid in the receptacle may pass through the pipe into the head, means to cause fluid in the pipe and head to pulsate with resulting expansion and contraction of the head, and a return tube for the fluid extending through the pipe with its ends communicating with the receptacle and head.

3. In a massaging device, a fluid receptacle, a pipe leading therefrom, a hollow head of elastic material, an open ended tube extending longitudinally in said head with one end portion projecting from the inner end of the head and connected with the other end of said

5 pipe, said tube being formed with side openings, a pressure exerting bulb intermediate the length of said pipe, and a return tube extending through said pipe and bulb with one end portion extending into said receptacle and its other end portion extending into the tube in said head.

10 4. In a massaging device, a fluid receptacle, a pipe leading therefrom, a hollow head of elastic material, an open ended tube extending longitudinally in said head with one end portion projecting from the inner end of the head and connected with the other end of said pipe, said tube being formed with side openings, a pressure exerting bulb intermediate the length of said pipe, couplings at the ends of the bulb connecting the bulb with sections of the pipe, oppositely opening check valves in said couplings, hollow stems extending 15 through said couplings, anchors for said stems engaged with said couplings, a tube in said bulb connecting said stems, and tubes leading from said stems through the pipe sections, one tube having an end portion extending into said receptacle and the other having an end portion extending into the tube in said head.

20 5. In a massaging device, a fluid receptacle, a pipe leading therefrom, a hollow head of elastic material, and open ended tube extending longitudinally in said head with one end portion projecting from the inner end of the head and connected with the other end of said pipe, said tube being formed with side 25 openings, a pressure exerting bulb intermediate the length of said pipe, couplings at the ends of the bulb connecting the bulb with sections of the pipe, oppositely opening check valves to control flow of fluid through said bulb, hollow stems extending through said 30 couplings, anchors for said stems engaged with said couplings, a tube in said bulb connecting said stems, and tubes leading from said stems through the pipe sections, one tube having an end portion extending into said 35 receptacle and the other terminating in a nozzle of rigid material loosely received in the tube in said head.

In testimony whereof I affix my signature.
